H. EDELMAN

BATHTUB APPURTEANCE

Filed Nov. 11, 1922

UNITED STATES PATENT OFFICE.

HENRY EDELMAN, OF PHILADELPHIA, PENNSYLVANIA, ASSIGNOR TO THE EDEL MANUFACTURING CO., OF PHILADELPHIA, PENNSYLVANIA, A CORPORATION OF DELAWARE.

BATHTUB APPURTEMENTANCE.

Application filed November 11, 1922. Serial No. 600,294.

To all whom it may concern:

Be it known that I, HENRY EDELMAN, a citizen of the United States, residing in the city and county of Philadelphia, State of Pennsylvania, have invented a new and useful Bathtub Appurtenance, of which the following is a specification.

My invention relates to a bath tub and consists of novel means for supplying the same with hot and cold water through a device common to both.

It consists also in adapting the supply device as an outlet for the overflow water and providing it with means for directing it therefrom to an overflow pipe.

It consists also of a valve for the drain or outlet of the tub adapted to be opened and controlled by novel mechanical means.

It consists also of details of construction as will be hereinafter set forth.

The invention is satisfactorily illustrated in the accompanying drawing, but the important instrumentalities thereof may be varied, and so it is to be understood that the invention is not limited to the specific details shown and described; as long as they are within the spirit or scope of the claims.

Figure 1 represents a vertical section of a portion of a bath tub, and of appurtenances embodying my invention.

Figure 2 represents a vertical section of the outlet portion of the overflow, and the drain, and trap pipe on an enlarged scale.

Figure 3 represents a vertical section on an enlarged scale of the supply spigot and connections detached from Figure 1.

Figure 4 represents a horizontal section of a portion on line 4—4 Figure 1, on an enlarged scale.

Similar numerals of reference indicate corresponding parts in the figures. Referring to the drawings.

1 designates a bath tub having the outlet 2 in the bottom thereof. Connected with said bottom at said outlet is the drain pipe 3 whose outer end is attached to the casting 4 which is supported below the floor on which the tub is placed and whose interior forms the chamber 5 in which is the seat 6 of the valve 7, the latter being connected with the lower portion of the overflow pipe 8 which passes upwardly from said chamber 5 through the top of the casting 4 and through the floor and extends above the latter to a

suitable height, said top and the adjacent portion of said overflow pipe being suitably packed as at 9 to form a water tight joint thereat but allowing said pipe to be raised to open the valve 7 and lowered to close the same.

Connected with the bottom of the casting 4 is the trap pipe 10 which leads to a sewer or other place of discharge of water from the tub.

In the upper portion of the overflow pipe is the vertical limb 11 of the elbow 12, the horizontal limb 13 of which passes through the lengthened slot 14 in the side wall of the overflow pipe 8 permits the latter to slide on said elbow in the vertical motions that may be imparted to said pipe, the shank 15 being packed at 17 with the wall of the opening in the tub which said nozzle occupies so as to form a water tight joint for the nozzle thereat, the packing or gaskets occupying the bosses 18 on the exterior of the spigot and embracing the adjacent wall of the opening in the tub.

Connected with the tubular shank 15 of the nozzle 16 by the plug 19 is the inclined branch pipe 19 which is connected with the pipes that are adapted to supply the tub with hot and cold water, said branch being in communication with the bore of said shank 15. Said pipes will be supplied with cocks or valves to turn on and cut off the hot and cold water while the nozzle 16 receives either or both as desired to direct the latter into the tub.

In the shank 15 below the place of its junction with the branch 19 is the depending guard 20 which is deflected towards the nozzle 16 leaving a passage 21 in said shank below the lower end of the guard and the adjacent portion of the wall of the shank, it being seen that the water enters the branch 19 flows over the guard 20 and so enters the nozzle. Should, however, the tub overflow and the water reach the level of the outlet end of said nozzle or above the same, the water will enter the nozzle flow through passage 21 into the shank 15 and enter the elbow 12 from which latter it is directed into the overflow pipe 8 and so escape therefrom.

through the trap pipe 10 into the sewer or other place of discharge. The shank 15 of the nozzle is also the overflow branch leading from the tub through said nozzle, this branch 5 with the supply branch 19 entering the nozzle and both communicating therewith. The divisional guard 20 is at or about the confluence of said branches 15 and 19.

It will here be noticed that the chamber 10 5 while forming a chamber for the valve 7 provides a space in the casting 4 to receive the water from the drain pipe 3 and so swirl around said chamber and wash the latter, while also washing the exterior of the valve 15 7 and its seat thus removing deposits that may have been occasioned at the relative places.

Supported on the wall of the bath room above the overflow pipe 8 is the box 22 on 20 whose walls is mounted the horizontally arranged rotatable shaft 23. Within the box is the pinion 24 which is secured to the shaft 23 and adapted to mesh with the rack 25 which is vertically movable in the box 22 25 and guided on the walls thereof.

Within the box there is also the fixed rack 27 which is placed at the side of the movable rack but removed therefrom, it being noticed that the shaft 23 is adapted to slide 30 transversely on the bearings in the opening 28 on one side of the box 22 and in the opening 29 on the opposite side thereof, the latter opening being in communication with the bore of the collar 30 which projects into the 35 box and forms a lengthened support for the shaft 23.

As said shaft is slidable as stated, the pinion 24 may be moved in part from the 40 movable rack 25 to the fixed rack 27 and engaged with the latter and thus the pinion is locked and prevented from rotation. Now it will be seen that when the valve 7 is to be opened the pinion 24 is rotated by the handle 31 of the shaft 23 whereby the rack 45 25 is raised and with it the stem 26, the overflow pipe 8 and the valve 7, the latter being raised from its seat 6 and accordingly opened allowing the water in the tub to escape therefrom through the pipe 3. The pinion 24 is 50 then pushed inwardly whereby it is engaged with the fixed rack 27, while also remaining engaged with the movable rack 25, and so the pinion is rendered non-rotatable and the movable rack 25 is locked thus holding the 55 valve 7 raised in its open position and the tub is drained. When the tub is to be refilled the pinion 24 is drawn from the fixed rack 27 and so remains engaged with only the movable rack 25 when the latter is permitted or caused to lower, whereby the valve 60 7 returns to its seat and so closes the drain or outlet of the tub, when water may be supplied to the latter through the nozzle as before.

Having thus described my invention what

I claim as new and desire to secure by Letters Patent, is:

1. In a bath tub appurtenance, a supply nozzle for said tub, a supply branch, and an overflow branch adapted to be connected 70 with the nozzle, both branches being adapted to communicate with the interior of the nozzle.

2. In a bath tub appurtenance, a supply nozzle for said tub, a supply branch, an overflow branch adapted to be connected with the nozzle, both branches being adapted to communicate with the interior of the nozzle, and a divisional guard at the confluence of the said branches. 75

3. In a bath tub appurtenance, a supply nozzle for said tub, a supply branch, an overflow branch adapted to be connected with the nozzle, both branches being adapted to communicate with the interior of the nozzle, 85 a valve and a slidale overflow member adapted to actuate said valve.

4. In a device of the character designated, an overflow pipe, an elbow the vertical limb of which is received in the upper portion of 90 said overflow pipe, said pipe having a slot through which the horizontal limb of said elbow passes, a nozzle on the tub connected with which is said last-named limb, and a branch pipe connected with said nozzle, said horizontal limb and branch being adapted to open into the interior of said nozzle.

5. In a device of the character designated, an overflow pipe, an elbow the vertical limb of which is received in the upper portion 100 of said overflow pipe, said pipe having a slot through which the horizontal limb of said elbow passes, a nozzle on the tub with which said last-named limb is connected, and a branch pipe connected with said 105 nozzle.

6. In a device of the character designated, an overflow pipe, an elbow the vertical limb of which is received in the upper portion of 110 said overflow pipe, said pipe having a slot through which the other limb of said elbow passes, a nozzle on the tub with which said last-named limb is connected, and a supply branch pipe connected with said nozzle, the shank of the said nozzle having therein a 115 depending guard at the confluence with said supply branch and deflected toward the nozzle.

7. In a device of the character designated, an overflow pipe, an elbow the vertical limb 120 of which is received in the upper portion of said overflow pipe, said pipe having a slot through which the other limb of said elbow passes, a nozzle connected with said last-named limb, an inclined branch pipe connected with said nozzle, a casting into which the said overflow pipe extends with a chamber around said overflow pipe, and a drain pipe connected with said casting and emptying into said chamber. 125

8. A supply nozzle for a bath tub, a tubular shank for said nozzle adapted to direct the supply water to the latter, a connection for said shank with the discharging overflow conveyor of the tub, an inclined branch pipe connected with said shank and a guard in said shank extending from a supply branch towards said nozzle, said guard being at the confluence of said shank and branch having between the same and said shank a passage adapted to direct the overflow water of the tub through said nozzle to said overflow conveyor. 45
9. In a bath tub, a supply nozzle for the tub, a supply branch leading into said nozzle an outer branch for the overflow water connected with said nozzle, and an overflow discharging member in communication with said conduit outlet branch, both branches being in communication with the interior of said nozzle. 50
10. In a bath tub, a slidable overflow member communicating therewith, a valve on said member, a chamber containing said valve, and a seat therefor, the said overflow pipe having a slot to permit of its removal and a drain pipe of the tub connected with said chamber, said valve being adapted to close and open said drain pipe by the movement of said overflow member. 55
11. In a bath tub, a slidable tubular overflow member, means including an elbow one limb of which is received in said overflow pipe for forming a communicating connection for said member with the interior of the tub, a valve on said member for the drain pipe of the tub, means for mechanically operating said overflow member, a chamber adapted to contain said valve and a portion of said overflow member and adapted to receive the drain and overflow waters of the tub, a connection for said chamber with the drain pipe of the tub, and a device for locking said means whereby said valve is held in open position. 60
12. In a bath tub, a slidable tubular overflow member, means including an elbow one limb of which is received in said overflow pipe for forming a communicating connection for said member with the interior of the tub, a valve on said member for the drain pipe of the tub, means for mechanically operating said overflow member, a chamber adapted to contain said valve and its seat and a portion of said overflow member and adapted to receive the drain and overflow waters of the tub, a connection for said chamber with the drain pipe of the tub, and a device for locking said means whereby said valve is held in open position. 65
13. In a bath tub, a slidable tubular overflow member connected with the tub, a valve thereon for the drain pipe of the tub, a casing adapted to contain a plurality of racks one movable and the other fixed, a pinion in said casing, a shaft carrying said pinion and being rotatably and slidably mounted on said casing, whereby said pinion may operate the movable rack and be engaged with the fixed rack thus locking the movable rack, and a connection for the movable rack 70 with said overflow member. 75
14. In a bath tub, a slidable overflow member, a valve thereon for the drain pipe of the tub, a water-supply member for the tub, a conductor for the overflow water leading from said water supply member and having a portion entering said overflow member, the latter having in its side a slot adapting the overflow member to slide on said portion. 80
